UNITED STATES PATENT OFFICE.

CHARLES W. BARNABY, OF NEW YORK, N. Y.

TYPE-WRITER.

1,308,386.

Specification of Letters Patent.

Patented July 1, 1919.

Application filed May 19, 1917. Serial No. 169,676.

To all whom it may concern:

Be it known that I, CHARLES W. BARNABY, a citizen of the United States, and resident of the borough of Richmond, county of Richmond, city and State of New York, have invented certain new and useful Improvements in Type-Writers, of which the following is a specification.

My invention relates to the feed mechanism of typewriting machines and the primary object of my invention is to provide improved mechanism of simple and compact form. The present application includes certain parts originally claimed in my copending application, Serial No. 112,951, filed August 3, 1916. The present application also discloses in part certain features claimed in my copending applications, Serial Nos. 273,865 and 273,866, filed January 29th, 1919.

Figure 1 is a front view of the feed mechanism, carriage, platen and auxiliary frame in which the carriage is mounted, the forward extensions of the auxiliary frame being cut away;

Fig. 2 is a section of Fig. 1 taken at a right angle to that figure and approximately on the line A—B of Fig. 1. A section of a part of the main frame is also shown in this figure on approximately the same line, A—B. Also a section through the center of the type-bar action and universal bar;

Figs. 3, 4, 5 and 6 are details of the escapement action;

Fig. 7 is an axial section through the main spring, main spring casing, carriage driving gear wheel and spring adjusting mechanism;

Fig. 8 is a front view of portions of the escapement mechanism illustrating a modification in the manner of applying the same;

Fig. 9 is a vertical section through the center of driving gear and rack, the gear being partly broken away to better show escapement parts.

The platen 1 is relatively mounted in carriage 2 and the carriage is reciprocably mounted on wheel 3 and bearing balls 4

which engage tracks forming a part of auxiliary frame 5. The auxiliary frame is reciprocably mounted in main frame 6 by means of a pair of links 7 at each side of the frames, the links being pivoted at the top of the sides of the main frame at 8 and to the bottom of the sides of the auxiliary frame at 9. Any suitable case shift device may be used to give the auxiliary frame its proper movement, in a direction at a right angle with the axis of the platen, to bring one or the other of type 10 on type-bar 11 into proper printing relation with the platen when the type-bar is thrown to printing position when in dotted outline 11'. 65

The type-bar is operated by key 12 attached to lever 13 pivoted to main frame at 14. A link 15 connects the key lever with lever 16 pivoted at 17 to an upper cross member 18 of the main frame. Lever 16 70 is pivoted at 19 to link 20 which in turn is pivoted at 21 to a lug forming a part of type-bar 11. The type-bar action shown on the drawings constitutes a part of the subject matter of my copending application 75 Ser. No. 128,298, filed October 28, 1916.

A toothed rack 22 runs the whole length of the carriage, shown broken away in Fig. 1, and is engaged by the driving gear 23. To the gear is attached spring case 24 and both are pivoted freely on a shaft which has a pivot 27 at one end journaled in a lug 5' on auxiliary frame 5 and a pivot 26 at the other end which is journaled in bearing bracket 28, the bracket being rigidly 85 secured to auxiliary frame 5 by two studs 29. A vibrating bar 30 has an upwardly extending arm, one branch 32 carrying the escapement dogs and another branch 33 engaging an opening in ribbon vibrator 34, 90 which is pivoted at 35 to a top bracket 36 of auxiliary frame 5. Two arms 37 extend forward from vibrating bar 30 carrying pawls 38 for operating ribbon spools (not shown) also carrying two wheels 39 95 which engage shelves 40 formed on upright members 41 of the universal bar 42. The lower, or normal position of the universal bar is determined by its feet 43 coming in contact with floor 6 of the main 100

frame. Springs 44 connected with arms 37 and floor of the main frame, hold vibrating bar 30 and its arms in normal position with wheels 39 resting on shelves 40 of the 5 universal bar, therefore any upward movement of the universal bar, causes movement of the vibrating bar and its arms.

The universal bar is constrained to an approximately vertical movement by a pair 10 of parallel links pivoted at one of their ends to each of the upright members 41 of universal bar, the other end of each link being pivoted to standards 45 extending from floor 6 of main frame to upper cross 15 member 18 of main frame, one being placed near each upright member 41 of the universal bar 42.

Space bar 47 extends along the front of the keyboard and connects with two space 20 levers 48 pivoted at 49 and engaging at their inner ends the under side of shelves 40 of the universal bar. Therefore when space bar 47 is pressed downward the universal bar 42 is raised to dotted position 25 42'. At the same time wheels 39 on the arms 37 of vibrating bar 30 are raised to dotted position 39' throwing the arm 32 toward the platen and putting the escapement into action as explained farther on.

30 Type-bar 11 is held in normal position by spring 50 which is anchored to the floor 6 of the main frame. The upper end of the spring is connected to a hook member 51 which engages a pivot at 52 on link 20. 35 When the writing action is put in operation and type-bar 11 swings toward printing position, spring hook 51 swings into and engages the inverted trough of universal bar 42, carrying it up to the dotted position 42', 40 thus putting the vibrating bar and its engaging members in operation.

The driving gear 23 acts also as an escapement wheel in conjunction with rack 22 which also performs a function in the escapement. Clock spring 53, Fig. 7, engages 45 a hooked pin 54 on the driving gear shaft, the outer end of the spring engaging hooked pin 55 at the inner periphery of the spring case. Worm wheel 25 is rigidly attached to 50 the gear shaft and is rotated by means of worm 56 journalled in lugs attached to bearing bracket 28. The main spring is thereby adjusted to the required tension. The 55 spring acts through the driving gear to force the rack in the direction indicated by the arrow on the rack, Fig. 1.

Normally, as shown in Figs. 1 and 3, the driving gear is held against rotating by the dog or pallet 57 pivoted at 58 to dog carrier 59 which in turn is pivoted at 60 to vibrating arm 32. Dog or pallet 57 is forced hard 60 against stop screw 61 attached to dog carrier 59, the carrier itself resting hard against pin 62 attached to vibrating arm 32, thus hold-

ing the driving gear in a fixed position. 65 Jaw 63, as well as jaw 64 when the latter is employed, is forward of and out of engagement with the teeth when in this normal position.

When the escapement is put into action by 70 the upward movement of wheel 39 attached to arm 37 of vibrating, or rocking bar 30, escapement arm 32 is thrown from its outer, or normal position 32 to its inner position 32', Fig. 4. In moving to this inner position jaw 63 passes into the tooth space with which it was in line in normal position, thus holding the rack and carriage in the same fixed position until the inner stroke is completed. In this inner position dog or 80 pallet 57 has passed to the rear of and out of engagement with driving gear 23. Having passed out of tooth space 65, Fig. 5, the dog or pallet is free to take its own normal position against stop screw 67 through the 85 action of spring 68. The action spring 69 tends to hold dog carrier 59 (removed in Fig. 5 to better show said dog or pallet and its spring and stops) in its normal position against stop pin 62. In its new position, 90 dog 57, Fig. 5, is back of and in line with tooth space 66, the next space beyond 65 which it had previously occupied. When dog arm 32' returns to its normal position 32, Fig. 4, dog 57 enters tooth space 66, Fig. 95 5, before jaw 63 leaves its tooth space in the rack. As soon as jaw 63 has left the rack, the main spring, which predominates over the weak dog spring 68, throws the driving 100 gear ahead until dog 57 strikes stop screw 61, which brings the parts again to the Fig. 3 relation, except that driving gear, rack and carriage have advanced one tooth.

Fig. 8 shows a modification in the application of my escapement in which the vibrating dog 57 engages the teeth of the rack instead of the teeth of the driving gear and the fixed jaw 78 attached to vibrating arm 32 engages the teeth of driving gear 23 instead of engaging the teeth of the rack. Otherwise the application and operation of the escapement is the same as the application shown in Figs. 3, 4, 5, 6. Normally (see Figs. 8 and 9), vibrating arm 32 is in its forward position with dog 57 in engagement 110 with the rack teeth and with jaw 78 forward of and out of engagement with the driving gear. As arm 32 moves to its backward position jaw 78 first enters its tooth space 115 in the gear, and later, just before arm 32 reaches its extreme back position, dog 57 passes back of and clear of rack 22 and through the action of the spring coiled around its shank is thrown back to position 57' against stop screw 67 in line with the 120 next tooth space, the same as in Fig. 5, where dog 57 has dropped a tooth space back from the position it occupied in Fig. 3. When

- arm 32, Fig. 8, moves forward to its normal position the dog moves well into the tooth space at 57' before jaw 78 passes out of engagement with the gear, so that as quickly as jaw 78 is clear of the gear the main spring acts through the gear to drive the rack forward in the direction indicated by the arrow, throwing the dog forward from dotted position 57' to 57 against stop screw 61.
- 10 Normally the extra fixed jaw 64 shown in Figs. 1 and 5 on arm 32 performs no function. It merely moves into and out of the tooth spaces in the driving gear, preferably without coming in contact with the teeth of the gear. While this auxiliary jaw does not come into engagement during the regular operation of the machine, I prefer to use it as a matter of safety, particularly when the carriage with rack attached is adapted 20 to be easily removed from the machine. For illustration, take Fig. 3 which has no extra jaw 64. Being in normal position with jaw 63 out of engagement and dog 57 locking the driving gear against turning, it is obvious that rack 22 may be lifted from engagement with the driving gear with impunity as long as the escapement mechanism is not disturbed, but, if the escapement is put into action through accidental or thoughtless operation of the space bar or a type key, dog 30 57 would be thrown out of engagement with the driving gear and the main spring would unwind in an instant. Referring to Fig. 5, if the extra jaw 64 is provided and the escapement put in operation to throw dog 57 out of engagement with the driving gear at a time when the rack 22 is removed, jaw 64 will have entered into engagement with a driving gear tooth, holding the driving gear 40 in position. When the escapement mechanism returns to normal position the driving gear will merely advance one tooth the same as though the rack was in place.
- To move the carriage to the right it is 45 only necessary to push handle 70, which is rigidly attached to the carriage, in the direction indicated by the arrow at that point. As the carriage starts backward dog 57 follows the tooth space in which it was situated 50 until it arrives at position 57' in contact with stop screw 67, Fig. 5. As the carriage moves still farther backward the gear tooth pressure against said dog 57 causes its carrier 59 to swing on its pivot 60 so as to allow the dog to slide over the top of the tooth as shown in Fig. 6. The carriage may thus be pushed backward to any desired position. The back spacing mechanism consists of the back space key 71 attached to lever 72 which 55 is pivoted at 73 to the floor of the main frame the lever carrying at its inner end the jaw 74 which hooks under roller 75. This roller is attached to lever 76 which is pivoted on stud 29. An arm 77 of lever 76 ex-
- tends backward under stud 29 and then upward. This arm is also pivoted on stud 29 and carries at its upper end the back spacing pawl 79. Spring 80 acts to throw the jaw end of the pawl upward but in the normal position of the back spacing mechanism, 70 pawl 79 is well out of engagement with driving gear 24, in which position the tail of pawl 79 rests on arm 81, extending backward from bearing bracket 28, and thus preventing spring 80 from throwing the jaw of 75 pawl 79 above its normal position.
- When the back space key is pressed down, roller 75 is thrown upward to 75' (see Fig. 1). As lever 76, to which this roller is attached, moves upward, pawl 79 is thrown 80 toward driving gear 24 and the tail of the pawl resting on arm 81 guides the jaw of the pawl into tooth space 82. Referring to Fig. 6, dot 83 represents the center of back space pawl pivot in normal position (see Fig. 85 1). 84 is the center of pawl pivot when said pawl is in dotted position 79' and has just entered tooth space 82. As the pawl pivot advances still farther to 85, tooth space 82 is turned backward to 82', the escapement 90 dog 57 during this time having turned first on its own pivot and then on pivot 60 of its carrier and left tooth space 66, now rests on the top of a tooth ready to drop into tooth space 65 when the driving gear is turned 95 slightly farther backward by the back space pawl upon the arrival of the back spacing mechanism at the limit of its movement. When pressure is removed from the back space key the back spacing mechanism is re- 100 turned to its normal position through the action of spring 86, one end of which engages bearing bracket 28 and the other end of which engages the upright part of arm 77.
- The release bar 87 (see Fig. 1) throws the escapement out of action when it is desired to move the carriage toward the left independently of the action of the escapement. The release bar is hung at one end on short arm 88 of lever 89 which swings on pivot 90 110 which is rigidly connected with the carriage, the other end of the release bar being hung on link 91 pivoted to the carriage at 92. A small roller 93 is mounted directly under release bar 87 upon an extension of the stud 115 for stop screw 61. This stud is attached to escapement dog carrier 59. The release is operated by seizing carriage handle 70 and lever 89 between finger and thumb which are squeezed together to bring the lever to position 89', handle 70 at the same time being pressed in the direction of the arrow to move the carriage slightly to the right. This operation throws the bottom of release bar to position shown by dotted line 87' and roller 93 is thereby pressed downward, throwing dog carrier 59 slightly lower than in Fig. 6 120 so that escapement dog 57 is clear of the

teeth of the driving gear. The escapement is thus thrown entirely out of engagement and as long as the handle and lever are held together between finger and thumb the carriage may be moved forward or backward to any desired position. When the carriage is in the desired position, thumb and finger are spread apart, allowing the lever to return to position 89 through the action of spring 10 94 and allowing the escapement dog to return to its engaging relation with the driving gear.

Interlocking elements are introduced into the mechanism of the escapement and of the 15 back spacer which prevent either from being put into motion after the other has started into action. Arm 95 (see Figs. 1 and 2), extends upward and slightly backward from back space lever 76, its front face being 20 slightly back of the rear face of the 96 portion of escapement arm 32. When the back spacing mechanism is put into action it only gets slightly started in its movement before arm 95 passes behind wall 96 of escapement 25 arm 32, thus preventing the escapement arm from moving backward which would lock the escapement mechanism against action. If the escapement mechanism is put into action first, the slightest movement of arm 30 32 brings the edge of wall 96 into the path of movement of back space lever arm 95, thus effectually locking the back spacing mechanism against operation until the escapement mechanism has returned to its normal 35 position.

Another interlocking element is introduced which prevents either one of the escapement or release mechanisms being put into action after the other has started to 40 act. An arm 97 extends backward from the jaw end of escapement arm 32. The extreme back end of arm 97 is just forward of release bar 87 and its top edge is just below the lower edge of the release bar, when both 45 are in normal position. When the escapement has barely started in motion arm 97 has started under the release bar, thus locking it against action and when the release is put into action first, release bar 87 only 50 moves slightly before it has passed downward behind arm 97, thus preventing the movement of escapement arm 32 backward and locking the escapement mechanism against action.

55 I claim:

1. In a typewriter, the combination with a reciprocable carriage provided with a rack, of escapement mechanism comprising, a pinion meshing with said rack, said pinion 60 being power driven, a vibratory lever provided with a double-jawed dog, the jaws of said dog being adapted by the movement of said vibratory lever to move into and out of positions respectively between adjacent teeth

of said rack and between adjacent teeth 65 of said pinion, and a vibratory dog movable into and out of engagement with said pinion.

2. In a typewriter, the combination with a reciprocable carriage provided with a rack, of a pinion meshing with said rack, means 70 for driving said rack by means of said pinion, and means for permitting a tooth by tooth escapement of said pinion, said escapement means including a vibratory arm carrying a dog with jaws for respectively engaging in said rack and pinion and a pawl which vibrates relatively to said dog for engaging said pinion.

3. In a typewriter, the combination with a reciprocable carriage provided with a rack, 80 of a pinion meshing with said rack, means for driving said rack by means of said pinion, and means for permitting a tooth by tooth escapement of said pinion, said escapement means including a vibratory arm 85 carrying a dog with jaws for respectively engaging in said rack and pinion and a pawl which vibrates relatively to said dog for engaging said pinion, and a vibratory arm 90 which carries said dog and pawl.

4. In a typewriter, the combination with a reciprocable carriage provided with a rack, of a pinion meshing with said rack, means for driving said rack by means of said pinion, and means for permitting a tooth by tooth escapement of said pinion, said escapement means including a vibratory arm 95 carrying an element adapted to engage and release said rack and a second element adapted to release and engage said pinion, one of 100 said engaging elements being adapted to vibrate relatively to said vibratory arm.

5. In a typewriter escapement, a rack, a gear meshing with said rack, a pallet engaging said rack, another pallet engaging said 105 gear, one of said pallets being yieldably mounted to permit a backward movement and means for alternately moving said pallets into and out of engagement with said rack and gear respectively, the escapement 110 movement of said yieldably mounted pallet being independent of the yieldable movement of its mount.

6. In a typewriter, an escapement mechanism including a carriage driving gear, a 115 vibratory arm, a dog carrier pivotally mounted on said vibratory arm, a dog pivotally mounted on said dog carrier and engaging said gear, and means for limiting the pivotal movement of said dog carrier in the 120 direction of the driving movement of said gear.

7. In a typewriter escapement, a rack, a driving gear in engagement with said rack, and means for permitting a tooth by tooth 125 escapement of said rack and driving gear, said escapement means including a jaw acting upon said rack, a vibratory dog acting

- upon said driving gear alternately with said jaw, and an auxiliary jaw acting upon the driving gear in unison with the action of the rack engaging jaw, whereby a complete escapement action is effected upon the driving gear when the rack is removed. 65
8. In a typewriter, the combination with a vibrating escapement means which includes an engagement dog, of an escapement release means including a portion which is normally in close corner to corner relation with and has a movement transverse to the movement of said engagement dog, said dog and escapement release means portion being so related that the starting of the escapement means upon its movement blocks said release means against movement until said escapement means has returned to normal position, and the starting of said release means upon its movement blocks said escapement means against movement until said release means has returned to normal position. 70
9. In a typewriter, the combination with a vibrating escapement means which includes an engagement portion, of a back spacing means which includes an engagement dog which is normally in close corner to corner relation with and has a movement trans- 75
- verse to the movement of said engagement portion of the escapement means, said escapement means engagement portion and back spacer engagement dog being so related that the starting of the escapement means upon its movement blocks said back spacing means against movement until said escapement means has returned to normal position, and the starting of said back spacing means upon its movement blocks 80
- said escapement means against movement until said back spacing means has returned to normal position. 85
10. In a typewriter, an escapement arm and a release bar having transverse movements relative to each other, said release bar and escapement arm being provided with means adapting them to cooperate with each other in the respective directions of their movements, so that when either is started on its movement the other is blocked from movement. 90
11. In a typewriter, an escapement arm and a back spacing arm having transverse movements relative to each other, and an interlocking portion attached to each of said arms in such positions that the engaging faces of said interlocking portions are normally in close corner to corner relation with each other in the respective directions of their movements, so that when either is started on its movement the other is blocked against movement. 95
12. In a typewriter, the combination with a vibratory escapement, of escapement re- 100
- lease means, the said escapement means being adapted throughout its movement to block the operation of said escapement release means and said escapement release means being adapted throughout its movement to block the operation of said escapement means. 105
13. In a typewriter, the combination of escapement means and back spacing means having interlocking elements co-operating between said escapement means and back spacing means to prevent one of said means being operated after an initial movement of the other said means has taken place. 110
14. In a typewriter, the combination with a reciprocable carriage, of carriage escapement means, and means for releasing said escapement means, said escapement means and escapement release means having co-operating parts which prevent the operation of either of said means by the movement of the other said means. 115
15. In a typewriter, the combination with a reciprocable carriage, of carriage escapement means, means for releasing said escapement means, and back-spacing means, said carriage escapement means and escapement-release means having interengaging elements co-operating to prevent the operation of either of said means after an initial movement of the other of said means, and said escapement means and back-spacing means having interengaging elements to prevent simultaneous operation thereof. 120
16. In a typewriter, a reciprocable carriage provided with a rack, a driving gear meshing with said rack, means for releasing said rack from said driving gear, and escapement means operating on said gear, said rack-releasing means and said escapement means having co-operative parts which prevent the operation of either of said means after the operation of the other of said means has been initiated. 125
17. In a typewriter, a reciprocable carriage provided with a rack, a gear meshing with said rack, means for driving said gear, escapement means operating on said gear, and back-spacing means operative on said gear, said escapement means and back-spacing means having parts adapted to cooperate in preventing the simultaneous operation of both of said means when either is actuated. 130
18. In a typewriter, a reciprocable carriage provided with a rack, a gear meshing with said rack, means for driving said gear, means for releasing said rack from said gear, escapement means operating on said gear, said releasing means and escapement means co-operating to prevent their simultaneous operation when an initial movement has been imparted to either, and back-spacing means, said escapement means and back- 135

spacing means coöperating to prevent the simultaneous operation of escapement means and back-spacing means after an initial movement has been imparted to either.

19. In a typewriter the combination with a reciprocable carriage, of an escapement mechanism therefor including a carriage drive gear, a dog carrier oscillatable about an axis, a dog oscillatable on said dog carrier about an axis parallel to the pivotal axis of said dog carrier, said dog engaging

said gear and adapted by the pivotal movements of said dog and dog carrier to permit a return movement of said carriage, and means for vibrating said dog and dog carrier laterally with respect to said gear for permitting the escapement of said carriage, said vibrating means being adapted to limit the escapement for each actuation of said vibrating means. 15

CHARLES W. BARNABY.
